UNITED STATES PATENT OFFICE

HAROLD WILLIAM PEARCE, OF PROVIDENCE, RHODE ISLAND, ASSIGNOR TO THE
WELSH MANUFACTURING COMPANY, OF PROVIDENCE, RHODE ISLAND, A CORPO-
RATION OF RHODE ISLAND

CLIP AND METHOD OF MAKING THE SAME

Application filed April 13, 1929. Serial No. 354,935.

The present invention relates to clips for writing implements, like mechanical pencils and fountain pens.

A clip of the above-described character is usually joined to the pen or pencil casing or cover at one end, and its free end is spring pressed into engagement with the casing or cover by its own resiliency. Sometimes, the free end is merely given a slight bend to facilitate slipping a pocket flap between the pen or pencil and the clip. Other clips, however, have a more efficient holding device in the form of a terminal hollow ball. As the clips are constituted of sheet material, it requires a number of manipulations to produce the ball, which adds to the difficulty and expense of manufacture.

An object of the present invention, therefore, is to improve upon clips of the above-described character, simplifying their construction and reducing their cost of manufacture. Other objects will be explained hereinafter and will be particularly pointed out in the appended claims.

In the accompanying drawings, Fig. 1 illustrates a clip constructed according to a preferred embodiment of the present invention, shown mounted upon a pen or pencil cover or casing; Fig. 2 is a view of a sheet-metal blank; Fig. 3 illustrates a step in the manufacture of the preferred clip from the sheet-metal blank of Fig. 2; Fig. 4 is a view corresponding to Fig. 3 of the completed clip; and Fig. 5 is an end view.

The sheet-metal blank comprises a body portion 2 and a terminal flange portion 4 joined together by a reduced neck 6. The portion 8 of the flange portion 4 is first bent transversely up out of the plane of the sheet, along the line of the neck 6, and around, as shown in Fig. 3, and the end 10 of the terminal portion 4 is then bent around substantially into contact with the neck 6. At the same time that these transverse bending operations are performed, the terminal portion 4 is bent longitudinally also to produce a bulging barrel-shaped effect, with the result that the terminal of the clip is provided with a rounded or more-or-less spherical surface 12 that has all the efficiency of the present-

day ball head, but that is nevertheless manufactured much more simply and at very greatly reduced cost.

The other end 14 of the clip is joined to the pen or pencil casing or cover 16 in any desired way.

Modifications will readily occur to persons skilled in the art, and all such are considered to fall within the spirit and scope of the invention, as defined in the appended claims.

What is claimed is:

1. As an article of manufacture, a clip of sheet material having a body portion, a terminal portion, and a reduced neck portion between the body portion and the terminal portion, the terminal portion being bent transversely up and around, with the end of the terminal portion disposed adjacent to the neck, the terminal portion being also bent longitudinally into the shape of a bulging barrel.

2. As an article of manufacture, a clip of sheet material having its terminal portion substantially bulging barrel shaped.

3. As an article of manufacture, a clip of sheet material having a body portion, a terminal portion, and a reduced neck portion between the body portion and the terminal portion, the terminal portion being substantially bulging barrel shaped.

4. A method of making a clip that comprises bending the terminal portion of a sheet of material out of the plane of the sheet along a line, bending the terminal portion transversely into barrel shape so that the end of the terminal portion shall be disposed adjacent to the line, and bending the terminal portion longitudinally into the shape of a bulging barrel.

In testimony whereof, I have hereunto subscribed my name.

HAROLD WILLIAM PEARCE.
